[57] CLAIM

The ornamental design for a shoe upper, as shown and
described.

DESCRIPTION

FIG. 1 is a right elevational view of the shoe upper;
FIG. 2 is a left elevational view of the shoe upper;
FIG. 3 is a top plan view of the shoe upper;
FIG. 4 is a rear elevational view of the shoe upper; and,
FIG. 5 is a front elevational view of the shoe upper.
The broken line showing of the sole in the FIGURES is for
illustrative purposes only and forms no part of the claimed
design.
